UNITED STATES PATENT OFFICE

ROBERT C. ANGELL, OF PRINCE BAY, NEW YORK, ASSIGNOR TO THE S. S. WHITE DENTAL MANUFACTURING COMPANY, A CORPORATION OF PENNSYLVANIA.

HEAD REST

Application filed March 23, 1929. Serial No. 349,352.

My invention relates particularly to head-rests for operative chairs such as dental chairs and the like and is especially directed to the clamp which adjustably supports the head-rest pads or pillows in different variable positions with respect to the back and seat of the chair.

The principal objects of my invention are to provide a head-rest structure and its support 10 with clamping means arranged to freely permit its adjustment in a wide range of positions and to rigidly clamp such head-rest structure and its support in any of such adjusted positions.

Other objects of my invention are to provide a clamp of such simplified construction that the parts may be readily assembled and removed; thus affording easy replacement of said parts.

Further objects of my invention are to provide a head-rest clamp with toggle means having a guided toggle knuckle supported for convenient replacement, and engaged in a predetermined relation with its support.

My invention further includes a head-rest clamp in which the locking members will automatically free themselves when released by movement of the lock-controlling handle or lever whereby any sticking or jamming of the parts is avoided.

Specifically stated, the form of my invention as hereinafter described comprises a head-rest having a support provided with a clamp and a head-rest pad or pillow carrying structure including a rod extended through said clamp and arranged to be pinched between clamping members which are arranged to rotate with respect to said head-rest support, said clamp having a toggle comprising a replaceable knuckle, relatively inclined toggle leaves or bars loosely engaged at their inner ends in hinged relation with said knuckle and engaged at their outer ends with friction shoes that frictionally engage the inner surface of a flange forming a pocket in one of said clamping members, and means tending to so shift said knuckle as to force said toggle leaves or bars toward a common plane and thereby force said shoes

outwardly into frictional engagement with the peripheral surface of said pocket.

My invention also includes all of the various novel features of construction and arrangement as hereinafter more definitely specified.

In the accompanying drawings, Figure 1 is a side elevational view of a head-rest assembly conveniently embodying my invention; Fig. 2 is a sectional elevational view of the assembly shown in Fig. 1 taken on the line 2-2 in said figure; Fig. 3 is a perspective view of one of the toggle leaves or bars which forms a component part of the locking mechanism of the clamp; Fig. 4 is a perspective view of one of the toggle shoes which cooperates with the toggle leaf or bar shown in Fig. 3; Fig. 5 is a central vertical sectional view taken through the support on the line 5-5 in Fig. 2; Fig. 6 is an inner face view of the cap which forms a component part of the clamp; Fig. 7 is an outer face view of the toggle frame as viewed from the right-hand side of Fig. 2; Fig. 8 is an inner face view of said toggle frame as viewed from the left-hand side of Fig. 2; and Fig. 9 is a transverse sectional view taken centrally through the toggle frame on the line 9-9 in Fig. 8.

In said figures, the head-rest assembly comprises the support 1 having the clamping head 2 which is provided with the relatively movable dome-shaped hollow cap 3 through which the tang 5 of the head-rest carrying vise 6 extends. The head-rest frame is of well known construction, being provided with the transverse bar 7 having the oppositely directed outwardly curved prongs 8 which rockably support the opposed head-rest pads 9 in a well known manner. The head-rest bar 7 is arranged for lateral adjustment between the jaws 10 and 11 and may be rigidly secured thereto in adjusted position by the screw 12 having the handle 13 arranged to bind said jaws upon said head-rest bar, as is common and well known in the art.

The support 1 is arranged to be mounted to slide up and down on a suitably provided slideway on the back of a chair and is provided with opposed dovetailed surfaces 15 which cooperate with correspondingly

shaped surfaces on the slide of the chair back, and said support may be secured thereto by the thumb screw 16 in a manner common in the art.

5 As shown in Figs. 2 and 5, the head 2 of the support 1 is circular in form and is provided with the recessed pocket 17 having the peripheral surface 19 against which the toggle shoes 20 are forced by the toggle leaves or bars 21, the inner ends of which are engaged in suitably provided grooves 22 in the toggle knuckle 23 which is carried by the toggle frame 25.

10 Said toggle frame 25 is provided with the slot 26 which serves as a guide for the toggle leaves or bars 21 and is provided with projections 27 and 28 which are arranged to extend into suitably provided recesses 29 and 30 in the free edge 32 of said cap 3, which is 15 also provided with aligned recesses 33 through which the tang 5 of the head-rest vise 6 extends with its flat side 35 bearing against the outer surface of the toggle frame 25.

20 The cap 3 is provided with projections 36 on one side thereof which bear against the outer surface of the toggle frame 25, the remaining inner surface of the edge 32 of said cap being spaced from the outer surface of said toggle frame by the tang 5, so that when 25 said cap and toggle frame are drawn together the tang is rigidly clamped therebetween.

25 The head 2, the knuckle 23 and the cap 3 are provided with central apertures 39, 40 and 41 respectively through which the retaining bolt 42 extends with its head 43 bearing against the outer flat surface 44 of the cap 3 and with its threaded end 45 projecting beyond the head 2. Mounted on the threaded end of the bolt 42 is the threaded hub 46 of 30 the adjusting lever 47 by the rotation of which the cap 3 and toggle frame 25 are drawn together toward the head 2 which effects binding of said tang 5 between the cap 3 and toggle frame 25 and also forces the 35 toggle leaves or bars 21 toward a common plane to effect frictional engagement of the toggle shoes 20 against the inner friction surface 19 of the head 2 of the support 1.

40 As shown in Figs. 2, 7, 8 and 9, the toggle frame 25 is provided with a central aperture 50 having the shouldered seat 51 which serves as a rest for the replaceable toggle knuckle 23 which may preferably be formed of hardened steel and which is arranged to 45 be held in said toggle frame against the seat 51 by the screws 52, the heads of which, as shown in Fig. 8, extend into suitably provided recesses 53 in the peripheral margin of the toggle knuckle, whereby said knuckle 55 is maintained in such position as to insure that the toggle bar receiving grooves 22 are disposed in a position normal to the slot 26 in the toggle frame 25.

50 My invention is advantageous in that by a 65 single movement of the hand lever 47 about

the axis of the bolt 42, which is prevented from rotation by the pin 55 projecting into the slot 56 therein, the cap 3 is drawn toward the toggle frame 25 to clamp the tang 5 in adjusted position and the toggle leaves or bars 21 are forced toward a common plane and their shoes are frictionally jammed against the friction surface 19 to form a rigid clamp structure which can be clamped with any desired force such as will absolutely prevent any movement between the component parts of the clamp.

70 Although I have elected to show a specific form of toggle arrangement including toggle bars in the form of leaves seated in grooves in the toggle knuckle and having separate bearing shoes, other forms of toggle might be employed with equal facility and, therefore, it is not desired to limit my invention to the precise details of construction and arrangement as herein set forth, as it is obvious that various modifications may be made therein without departing from the essential features of my invention as defined in the appended claims.

75 Having thus described my invention, I claim:

1. A head-rest assembly comprising a head-rest carrier having a tang and a support having a clamp, comprising a head rotatably associated with relatively movable members rotatable with respect to said head and in which said tang may be adjustably engaged, toggle means disposed between said head and associated members, and means arranged to draw said members together towards said head to effect actuation of said toggle means and thereby rigidly engage said tang in adjusted relation with respect to said support.

80 2. A head-rest assembly comprising a head-rest carrier having a tang and a support having a clamp affording a pocket, a relatively rotatable member opposed to said pocket and having a guide into which said tang is arranged to extend, toggles cooperative with the peripheral surface of said pocket, and means arranged to draw said member toward said pocket to contemporaneously effect jamming of said toggles in said pocket, and the rigid engagement of said tang with respect to said clamp.

85 3. A head-rest assembly comprising a head-rest carrier frame having a tang and a support having a clamp provided with a circular pocket, a relatively movable cap for said clamp, a toggle guide interposed between said cap and said pocket, and toggles having friction shoes engaged with the peripheral wall of said pocket, and means arranged to draw said cap and toggle guide together toward said pocket to effect clamping of said tang and the frictional engagement of said shoes to afford a rigid assembly in which the component parts are in effect integrally united.

4. A head-rest assembly comprising a head-rest carrier frame having a tang and a support having a clamp provided with a circular friction surface and including a relatively movable cap having alined recesses, a toggle frame associated with said cap and having means interlocked therewith to prevent relative rotation, a knuckle carried by said frame, friction shoes arranged to frictionally engage said friction surface, toggle bars extending between said knuckle and said friction shoes, and means arranged to draw said cap toward said frame to effect rigid engagement of all of the parts of said assembly. 70
5. A head-rest assembly comprising a head-rest carrier frame having a tang and a support having a clamp provided with a circular pocket and including a relatively movable cap having alined recesses therein through which said tang is arranged to extend, a toggle frame having means interlocked with said cap to prevent relative rotation and affording a toggle knuckle, toggle bars interposed between the peripheral surface of said pocket and said knuckle disposed in relatively angular relation to each other, and means tending to draw said cap and toggle frame together to rigidly lock the clamp members in rigid relation. 80
6. A head-rest assembly comprising a head-rest carrier frame having a tang and a support having a clamp including a head provided with a circular inner surface, a relatively movable cap having alined recesses therein through which said tang is arranged to extend, a toggle frame having means interengaged with said cap to prevent relative rotation, a replaceable toggle knuckle carried by said toggle frame, toggle bars engaged with said knuckle and having friction shoes arranged to frictionally engage the inner surface of said head, a bolt extended through said cap and head, and a hand lever threadedly engaged with said bolt and arranged to draw said cap and toggle frame together toward said head and thereby effect rigid clamping of the assembled parts together. 85
7. A head-rest assembly comprising a head-rest carrier frame having a tang and a support having a clamp affording a head provided with a circular inner surface and including a cap having alined recesses therein through which said tang is arranged to adjustably extend and having projections at one side thereof, a toggle frame resting against said projections and extending free from the balance of said cap but having means interengaged with the projections to prevent relative rotation, a toggle knuckle removably engaged with said frame and having transverse slots therein, toggle bars disposed in said slots, friction shoes associated with said toggle bars arranged to frictionally engage the inner surface of said clamp, a bolt ex- 90
- tended through said clamp, means arranged to prevent rotation of said bolt in said clamp, and a hand lever in threaded engagement with said bolt arranged to draw said cap and frame together toward said head to effect a rigid engagement of the component parts of said assembly. 95
8. A head-rest assembly comprising a head-rest carrier frame having a tang and a support having a clamp provided with a head having a circular inner surface, a relatively movable cap for said clamp, a slotted toggle frame spaced from said cap and arranged to bear upon said tang and having means arranged to interengage said cap to prevent relative rotation, a bearing knuckle carried by said toggle frame, toggle bars disposed in the slot in said toggle frame and arranged to rock on said knuckle and cooperative with said inner surface when moved toward a common plane, to prevent relative rotation of said cap with respect to said head, and a bolt having means arranged to draw said cap and frame together toward said head to rigidly clamp the component parts of said assembly together. 100
- In witness whereof, I have hereunto set my hand this twenty-first day of March, A. D. 1929. 105
